FIG.1

FIG.2

FIG.3

FIG.4

FIGURES 1, 2 and 3 are perspective views of a drawstring handbag embodying my new design, each taken at a relative angular displacement of 120°, and all showing the bag in expanded, open condition; and

FIGURE 4 is a top plan view, also showing the bag in expanded, open condition.

The characteristic feature of my new design resides in a drawstring handbag or the like having a plurality of variously shaped open pockets on its exterior, all as shown.

I claim:

The ornamental design for a drawstring handbag or the like, as shown and described.
